UNITED STATES PATENT OFFICE.

CLARENCE E. MORRISON, OF. ALBANY, NEW YORK.

ROTARY DUPLICATING-MACHINE.

1,227,176.

Specification of Letters Patent.

Patented May 22, 1917.

Application filed July 3, 1916. Serial No. 107,337.

To all whom it may concern:

Be it known that I, CLARENCE E. MORRISON, a citizen of the United States, residing at Albany, in the county of Albany and State of New York, have invented certain new and useful Improvements in Rotary Duplicating-Machines; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in rotary duplicators for the reproduction of typewritten letters and the object in view is to produce a simple and efficient device of this nature so constructed that the cylinder may be detachable whereby it may be possible to print off a few letters, if desired, and replace the same with another cylinder for printing another form of letter.

Heretofore in duplicating machines, strips have been utilized which are connected to the ends of the impression roll and, in order to throw the cylinder out of use or to hold the roll away from the cylinder for an interval at each revolution, it is necessary to exert an extra pressure upon the strips, whereas with the present invention the operation is reversed, pressure being relieved by a cam instead of requiring additional power.

My invention comprises a simple and efficient apparatus of this nature having various details of construction, combinations and arrangements of parts which will be herein-after fully described, shown in the accompanying drawings and then specifically defined in the appended claims.

I illustrate my invention in the accompanying drawings, in which:

Figure 1 is a top plan view of the invention.

Fig. 2 is an end view.

Fig. 3 is a sectional view on line 3-3 of Fig. 1.

Fig. 4 is a sectional view longitudinally through one end of the cylinder.

Fig. 5 is a cross sectional view through a member connecting the ends of the cylinder.

Fig. 6 is a top plan view of an impression roller and frame holding the same.

Fig. 7 is a detail perspective of a part of the apparatus.

Reference now being had to the details of the drawings by numeral, 1 designates the frame of the apparatus in which a shaft 2 is journaled, said shaft carrying two spider cylinder heads, designated by numeral 3, said heads having each a flange 4, one being shown clearly in Fig. 4 of the drawings, and 5 designates the circumference of a cylinder which is made preferably of metal and has its ends 6 turned into rolls and which engage over the ends of the rib 7 formed upon the edges of the flanges 4, shown clearly in Fig. 3 of the drawings. A wooden strip 8 is mounted in recesses 9 formed in the inner faces of the cylinder heads and being held therein by screws 10 and serving as means for holding the cylinder heads in place. Pins 11 project from the opposite faces of said strip 8 and over which one end of the impression sheet 12 is caught. A sheet of fabric 12^x, forming a suitable backing for the impression sheet has loops formed at its ends by turning the latter upon themselves and stitching the same to the body of the fabric, and 12' designates wires which are passed through said loops and serve to hold the sheet of fabric against the outer surface of the cylinder. A bail-shaped member, designated by numeral 13, has its angled ends 14 pivotally mounted in apertures in the cylinder heads, and grooves 15 and 16 are formed in the end of the cylinder head and in which the bail may be held in the different positions shown in Figs. 3 and 4 of the drawings. When the bail is adjusted in the position shown in Fig. 3, it is adapted to engage and hold the free end of the impression sheet 12 upon the outer surface of the sheet of fabric, 95 as shown.

An oscillating frame, designated by numeral 15', has spindle ends 16' pivotally mounted in said frame and carries in the arms 17 thereof the spindle ends of the roller 18, shown clearly in Fig. 6 of the drawings, and which is adapted to bear frictionally against the impression sheet upon said cylinder. A gear wheel 18' has a hub portion 19 journaled in a suitable bearing 100 in the frame and the teeth of said gear wheel are in mesh with the teeth of a pinion 20 mounted upon the stub shaft 21 upon the frame and a handle 22 is fixed to the said shaft 21. Said frame 15', it will be noted, 110

has an arm 23, apertured as at 24 for the reception of the pin 25 upon which the tilting lever 26 is mounted which carries a grooved friction roller 27, adapted to contact with the cam flange 28 of the gear wheel 18'. An adjusting screw 29 is mounted in an aperture in the arm 23 and upon the end of said screw the lever 32 is pivoted, and a suitable spring 35 is interposed between a washer 35* upon said screw 29 and the arm 23 and provided so that, when said screw 29 is turned in one direction or the other, the tension of the spring may be increased or decreased for the purpose of regulating the pressure that it may be desired to have the impression roller 18 bear against the cylinder. Said lever 32 has a lug 38 projecting therefrom and adapted to bear against the lever 26 to limit the swinging movement of said lever 32 in one direction.

Projecting from the under surface of the lever 32 is a lug 40 which is convexed and is adapted to serve as a means for guiding the lever 32 when being swung laterally upon the pin 29, the convexed edge of the lug 40 coming in contact with the rear edge of the arm 23. Suitable gages 41, regulated by set screws 42, are mounted upon the table 30 against which the paper to be printed upon is adapted to be held.

Projecting from the face of one cylinder head 3 is a lug, preferably of V-shape, as shown in dotted lines in Fig. 2, and which is adapted to engage a similar slot 51 formed on the face of the cam disk and which lug and slot are provided for the purpose of causing the cylinder and gear wheel having the cam flange to rotate together and also serving to hold the parts in proper position so that the apertures in the cylinder heads will register for the purpose of receiving the shaft 2.

In operation, the parts being assembled as shown, one end of the impression sheet 45 is caught over the pins 11 upon one side of the strip 8, passed about the cylinder and its other end held by the bail 13 in the manner shown in Fig. 3 of the drawings. The paper to be printed upon is placed upon 50 the table and fed frictionally between the roller 18 and the impression sheet upon the cylinder. When the cam edge of the disk 28 comes adjacent to the friction roller 27, the pressure will be released from the impression roller 18 and which action would 55 take place after the sheet had been printed and, when it is desired to throw the impression roller away from the cylinder when not in use, the lever 32 is swung laterally which will allow the impression roller 60 to drop down out of contact with the cylinder.

By the provision of a rotary duplicating

machine embodying the features of my invention, it will be noted that a simple and 65 efficient means is provided whereby the cylinder may be easily and quickly removed and replaced by others should it be desired to do so and which would be the case where it is desired to print off only a few hundred 70 letters at one time, in which event the cylinder could be filed away with the stencil and other letters could be printed at any time, if desired, by simply replacing the cylinder. The removal of the cylinder is 75 accomplished by unscrewing the nut upon the end of the shaft 2 which will permit the shaft to be removed from the cylinder, allowing a new cylinder to be inserted by replacing the shaft to the position shown 80 in Fig. 1 of the drawings. By this means, only as many letters as may be desired at a certain time may be struck off, thus economizing in the printing of uncertain quantities of letters and, by having different cylinders, parts of letters may be printed in different colors of ink and which will not necessitate the removing of pads and cleaning up at each time of printing.

What I claim to be new is:—

1. A rotary duplicating machine comprising a frame, a rotatable detachable cylinder mounted therein and upon which an impression sheet is adapted to be held, a rocking frame, an impression roller carried 95 thereby and held yieldingly against the surface of the cylinder, a cam disk rotating with the cylinder, a lever pivotally mounted upon the rocking frame, a pulley pivotally mounted upon said lever and frictionally 100 engaging the cam disk, a set screw carried by the arm of said lever, and a lever pivoted upon the rocking frame and against which said set screw is adapted to bear.

2. A rotary duplicating machine comprising a frame, a rotatable cylinder mounted thereon and adapted to carry an impression sheet thereon, a rocking frame, an impression roll pivotally mounted thereon, an adjusting screw upon the rocking frame, a spring upon said screw for regulating the pressure of the impression roll against said cylinder, a lever pivoted upon the rocking frame, a grooved pulley carried by said lever, means for adjusting the latter relatively to said rocking frame, a cam disk rotating with the cylinder and against which the pulley is adapted to contact, and gear mechanism for rotating the cylinder.

In testimony whereof I hereunto affix my signature in presence of two witnesses.

CLARENCE E. MORRISON.
